BERT R. BENJAMIN,
INVENTOR.

BY *Grace L. Schuyler*

ATTORNEY

UNITED STATES PATENT OFFICE.

BERT R. BENJAMIN, OF OAK PARK, ILLINOIS.

GOLF-TEE.

1,215,316.

Specification of Letters Patent.

Patented Feb. 6, 1917.

Application filed January 24, 1916. Serial No. 73,966.

To all whom it may concern:

Be it known that I, BERT R. BENJAMIN, a citizen of the United States, residing at Oak Park, in the county of Cook and State of Illinois, have invented certain new and useful Improvements in Golf-Tees, of which the following is a full, clear, and exact specification.

My invention relates to golf tees.

It has among its objects to provide an improved tee of the sanitary type, by the use of which greater accuracy in driving is obtained. A further object of my invention is to provide an improved tee of the sanitary type which may be readily manufactured at reduced expense. A still further object of my invention is to provide an improved sanitary type tee adapted to be formed in cards comprising a plurality of the tee blanks so that the same may be conveniently handled and, if desired, the card may be used as a score card, and the tee blanks comprising the same may be subsequently severed therefrom and connected and used as tees on following rounds. These and other objects of my invention will be hereinafter more fully brought out.

In order that my invention may be fully and clearly disclosed, I have shown for purposes of illustration in the accompanying drawings, one embodiment which the same may assume in practice.

In these drawings:

Figure 1 is a plan view of a blank from which a tee is formed.

Fig. 2 is a plan view of a tee blank having its ends connected in such a manner as to form a tee.

Fig. 3 is a side elevation of the tee shown in Fig. 2.

Fig. 4 is a side elevation of a tee with a ball seated thereon.

Fig. 5 is a plan view of a plurality of severally connected tee blanks of the character shown in Fig. 1 suitably printed and cooperating to form a score card.

The tee shown in these drawings is formed from a single straight blank or strip 1 of flexible material, preferably paper, and provided with oppositely disposed trans-

verse slots or slits 2 adjacent each of its ends and oppositely disposed guiding notches 3 leading to these slits and provided in the opposite edges of the strip. As shown, these slits 2 extend partway across the opposite ends of the strip 1 and form oppositely extending wing portions or flaps 4 upon the extreme ends of the blank.

When it is desired to form one of the blanks 1 into a tee, the same is bent into a cylindrical form until the slits 2 are brought into alinement, one above the other, the flaps 4 then being disposed within the guiding notched portions 3, whereupon, by simply pushing the ends of the strip together until movement of the same is limited by the mutual engagement of the ends of the slits 2, a substantially cylindrical tee is formed having a tubular ball seat and its ends interlocked and connected in such a manner as to prevent accidental displacement.

Attention is here directed to the fact that through my improved construction a tee is produced which increases the accuracy of the drive ordinarily obtainable when using a tee of the sanitary type, the same being cylindrical in shape, as distinguished from conical, so that when a ball thereon is struck the far side of the tee may readily turn over or collapse and the tee be bent into an elliptical form in such a manner as to eliminate all resistance to the flight of the ball or to the movement of the club. It will also be noted that due to the improved connection between the ends of the blank, while these ends are securely attached, there is a certain amount of play permitted between the same which likewise facilitates this collapsing movement of the tee when the ball is struck.

In practice it has been found that different players use tees of different heights. I have accordingly provided means whereby my improved tee may be adapted to support the ball at different heights and thereby be adapted to use by all players. I attain this result in my improved construction by providing at one end of each strip 1, a plurality of slits 2 and notches 3 disposed adjacent each other so that if the player desires to use a small tee and thereby lift the ball

higher from the ground, or a large tee and thereby lower the ball to the ground, he may do so by simply connecting different sets of slits. Obviously, while I have herein only shown a pair of slits at one end of the blank, any desired number of slits may be used for this purpose and the same may be provided on either or both ends of the strip, as circumstances may show to be desirable.

10 In the manufacture of my improved tee a plurality of tee blanks 1 of the character shown in Fig. 1 are preferably formed in a card 5, the members 1 being disposed one above the other and severably connected, as 15 by transversely disposed division lines 6, preferably formed by weakening a card or perforating the same in any approved manner so that the individual blanks 1 may be torn off when desired. By forming the tees 20 in such a card I am able not only to provide the tees in convenient form for handling, but at the same time use the card as a score card, the card for this purpose being divided vertically into a plurality of parallel columns 25 suitably marked at the top, as indicated in Fig. 5, to indicate the holes, the distances, the par for the holes, the players' scores, and the like, and the several blanks or strips 1 preferably being transversely lined and having the numbers of the holes, 30 the yards, the par for the hole, etc., printed thereon in vertical columns, in such a manner as to facilitate the entry of the various scores and enable a plurality of tee blanks 35 to coöperate and form a standard score card.

Obviously, this card may be very readily folded in a compact space, if desired, by folding the same along the transverse division lines 6 after the fashion of an accordion 40 plait, or otherwise, so that it may be readily carried in the player's pocket. It is also obvious that by changing the character of the weakened lines the card may be made so stiff as to be in effect a single sheet and 45 have sufficient rigidity to enable even greater readiness of entry of the scores. It is also obvious that by forming the weakened lines 6 as shown herein, the edges of the tees will be made serrated by the tearing off of 50 the same in such a manner as to provide a serrated ball seat. It will also be noted that in the manufacture of my improved tee it is possible to make the same by a die which in a single operation weakens the 55 sheet 5 along the lines 6 and simultaneously cuts the slits 2 and notches 3, the card either being printed for the score before being operated upon by the die, or afterward, as best suits conditions. It is also to be noted 60 that the tees may be formed of sheets of paper of standard rectangular form without any waste whatsoever, the entire sheet being used, and that further economy is produced by the availability of the old score

cards as tees, the several blanks or strips 65 1 being severable from the card and adapted to use as tees on following rounds.

While I have in this application specifically described one embodiment which my invention may assume in practice, it is, of 70 course, to be understood that this embodiment is used for purposes of illustration and that the invention may be embodied in other forms without departing from its spirit, it being my intention to include all 75 such modifications within the scope of the appended claims.

What I claim as my invention and desire to secure by Letters Patent is:

1. A golf tee blank comprising a straight 80 strip of flexible material carrying means for pivotally connecting its ends.

2. A golf tee blank comprising a straight strip of flexible material having oppositely disposed transverse slits in its opposite 85 ends.

3. A cylindrical laterally yieldable golf tee formed of a straight strip of flexible material having its ends pivotally connected. 90

4. A cylindrical golf tee formed of a straight strip of flexible material having co-operating interlocking portions pivotally connecting its ends.

5. A cylindrical golf tee formed of a 95 straight strip of flexible material, having connecting means on its ends permitting relative angular movement thereof.

6. A golf tee comprising a straight strip of flexible material having oppositely disposed transverse slits in its opposite ends and notches between said slits and leading thereto. 100

7. A golf tee having a tubular ball seat and connected ends, and means for adjusting the point of connection of said ends to vary the size of said seat. 105

8. A golf tee of cylindrical form and having interlocking ends inter-engageable in a plurality of positions to vary the elevation of the ball. 110

9. A combined tee card and score card comprising a plurality of severably connected tee members disposed as collectively to form a score card. 115

10. A combined tee card and score card comprising a plurality of severably connected substantially straight tee blanks.

11. A golf tee card comprising a plurality of severably connected substantially straight flexible tee members, each carrying means for attaching its ends together. 120

12. A golf tee card comprising a plurality of severably connected flexible tee members, each having interlocking means 125 on its ends.

13. A golf tee card comprising a plurality of severably connected substantially

straight flexible tee members, each having oppositely disposed transverse slits in its opposite ends.

14. A combined tee card and score card comprising a plurality of severably connected tee members carrying portions of the scoring indicia and coöperating to form a score card.

15. A combined tee card and score card comprising a plurality of substantially 10 straight severably connected tee members, each being suitably imprinted and coöperating with its fellows to form a score card.

In testimony whereof I affix my signature.

BERT R. BENJAMIN.
